AMMUNITION CONVEYER

William Thomas, Waterbury, Conn., assignor to
 The Waterbury Tool Company, Waterbury,
 Conn., a corporation of Connecticut

Application August 25, 1936, Serial No. 97,801
 Renewed October 28, 1939

19 Claims. (Cl. 89—46)

1

This invention relates to power transmissions and more particularly to a conveyer for delivering articles from one station to another wherein a fire hazard is present at one station and in which it is desired to prevent the possibility of flame transmission between the two stations at all times, while permitting the continued passage of articles between the stations. The invention is particularly adapted to delivering ammunition aboard ship from an ammunition storage compartment to a position at the guns for use therein, although it will be understood that the invention may be adapted to other uses wherein similar conditions and problems are encountered.

It is customary in war vessels to locate the ammunition magazines or storage chambers in the lower part of the ship where the possibility of their contents being exploded by enemy projectiles is most remote. The guns which use the ammunition being situated on the upper decks of the ship, either in turrets or on deck mountings, it is necessary to provide means for conveying ammunition from the magazine to a position near the guns where it may be readily placed in the guns as needed.

Various types of conveyers have been heretofore provided for this purpose and where high rates of delivery to rapid firing guns are required, the so-called dredger type ammunition hoists have marked advantages over other types in use. Such a hoist usually comprises an endless chain conveyer which is encased in a continuous tubular hoist trunk or casing extending through the ship from the loading station in or adjacent the magazine to the unloading station adjacent the gun. This continuous hoist trunk provides a conduit which introduces the possibility of flame transmission to the magazine whenever accidental explosions occur at the gun or whenever an enemy projectile explodes in or near the hoist trunk.

In order to break this continuous path for flame travel to the magazine, it has been found necessary heretofore to deliver the ammunition in two stages by two entirely independent ammunition hoists with a transfer station where the ammunition is carried manually from the delivery end of the lower hoist to the loading end of the upper hoist. This construction, while satisfactory from the standpoint of safety of the installation and effectiveness to prevent the transmission of flare-backs to the magazine, adds considerably to the weight and cost of the installation since each of the two sections of

2

the hoist must be provided with its own independent drive mechanism. Furthermore additional crew is required for handling ammunition at the transfer station, which not only increases the number of men required for each gun to be fired but presents also a retarding element in the delivery of ammunition since it introduces one more place for unavoidable human errors and delays to interfere with the intended operation of the hoist.

It is an object of the present invention to provide a conveyer particularly adapted for delivery of ammunition directly between a loading station adjacent the magazine and an unloading station adjacent the gun by which ammunition may be delivered through a continuous closed casing whereby transmission of flare-backs to the loading station may be prevented without requiring an intermediate transfer station.

It is also an object to provide a conveyer for delivering articles between two stations which are separated by a flame-proof wall having an opening at one station adjacent the conveyer and in which is incorporated means for passing articles through the opening while maintaining a flame-proof seal at all times.

A further object is to provide a loading station for a conveyer whereby articles may be loaded on the conveyer including means for maintaining a flame-proof seal around the conveyer at all times.

Further objects and advantages of the present invention will be apparent from the following description, reference being had to the accompanying drawings wherein a preferred form of the present invention is clearly shown.

In the drawings:

Fig. 1 is a diagrammatic cross section of a ship incorporating a preferred form of the present invention.

Fig. 2 is a partial sectional view on line 2—2 of Fig. 3.

Fig. 3 is a front view of a conveyer loading station, portions of the mechanism being broken away for clearness.

Fig. 4 is a diagrammatic view of the driving and controlling mechanism for the conveyer illustrated in Fig. 1.

Fig. 5 is a cross section on line 5—5 of Fig. 2.

Fig. 6 is a cross section on line 6—6 of Fig. 7.

Fig. 7 is a cross section on line 7—7 of Fig. 2. Referring now to Fig. 1 there is indicated diagrammatically a portion of a longitudinal section of a war vessel having superimposed decks 10 of usual construction, the spaces between which are

divided by partitions 12 into suitable compartments. Indicated at 14 is a deck gun and at 16 a revolving turret having two or more guns 18 mounted thereon in the usual fashion. Adjacent the gun 14 is mounted the delivery head 20 of a dredger type ammunition hoist 21 having a trunk 22 extending downwardly through the vessel to a compartment 24 which may be either a magazine compartment for the storage of ammunition or a handling room adjacent such a compartment and in which is located the loading end 25 of the hoist 21 together with suitable driving mechanism for the hoist. In the turret 16 is mounted a delivery head 26 of a second dredger type ammunition hoist 27 having a trunk 28 extending vertically downward to a compartment 30 similar to the compartment 24, in which is located the loading end 32 and the necessary driving mechanism for the hoist 27. The hoist trunk 28 is shown secured to the top deck 10 at the center of rotation of the turret 16 and is stationary relative to the turret although it will be understood that the ammunition hoist 27 may be mounted to revolve with the turret 16 if desired.

Referring now to Figs. 2 through 7 wherein the construction of the loading ends 25 and 32 is illustrated in detail, there is shown a casing 34 forming the lower end of the hoist trunk to which the casing 34 may be tightly sealed at the flange 36. The casing 34 serves not only to enclose the drive sprockets 40 and hoist chain or conveyer band 38, having conveyer lugs 39, but also as a mounting for the hoist driving and control mechanism. The latter may be of any suitable construction. The form of drive mechanism and control therefor illustrated comprises a fluid motor 42 adapted to drive the sprockets 40 through a worm drive 44. A variable displacement pump 46 and auxiliary pump 48 are driven by an electric motor 50 to supply fluid to the motor 42 through a control unit 52. The control unit 52 is constructed to control the displacement of the pump 46 and to control communication between the pump 46 and the motor 42 through conduits 54 in a manner to provide for automatically moving the hoist chain 38 through one flight whenever a starting "short" of fluid from the auxiliary pump 48 is admitted to the device 52 through a control conduit 56.

For this purpose the control unit 52 comprises a body 41 having a cylindrical bore 43 in which is mounted a spool valve 45 for the purpose of blocking or opening the passage of oil between the conduits 54 and conduits 47. A second cylindrical chamber 49 carries a spool valve 51 for the purpose of reversing the flow between the conduits 47 and a pair of conduits 53 which lead to the fluid motor 42. The body 41 also has at its upper end a bore 55 in which is mounted a spool valve 57 for controlling the stroke regulating fluid motor of the pump 46. A conduit 59 extends from the auxiliary pump 48 to the upper end of the bore 55 while a conduit 61 enters the bore 55 at its mid-portion. The valve 57 is adapted to selectively control and reverse the connections of the conduits 59 and 61 with a pair of conduits 63 and 65 leading to opposite ends of the stroke regulating mechanism at the pump 46. The valves 45 and 51 are formed integrally upon a common stem having an enlarged portion 67 around which is slidably mounted a lift piston 69. The latter has a cylindrical upper portion 71 slidably fitted in a chamber 73 which communicates with the upper end of the bore 55 through a passage 75 formed in the spool of valve 57. The 75

piston 69 has a portion 71 of larger diameter than the portion 71 and slidably fitted in a chamber 79 to which the conduit 56 leads. The bottom wall of the piston 69 is provided with an opening 45 forming a clear passage around the stem of valve 45 and having a seat on which the enlarged portion 67 of the stem is adapted to rest for the purpose of closing this passage. The space inside the piston 71 communicates with the tank through a passage 81 formed in the stem of the valve 45. At its lower end the valve stem has a roller 83 acting as a follower for a cam 85. The latter is connected by a suitable drive means not shown to the shaft of the sprockets 40 so that the cam 85 makes one revolution while the chain 38 travels through one flight distance. The cam 85 has a depression in which the roller 83 is shown at rest. In this position the valve 45 is completely closed while the valve 57 connects the conduit 63 to the pressure line 59 and the conduit 65 to the tank line 61. To either side of this depression are elevated portions 87 which hold the valves in such a position that the valve 45 is opened to a considerable degree while the valve 57 still connects conduit 63 with conduit 59 and conduit 65 with conduit 61. The remainder of the periphery of the cam 85 is raised still further so as to completely open the valve 45 and to reverse the connections at the valve 57. When the valves are raised to this upper extreme position the valve stem has been lifted higher than it is possible to lift the piston 69, so that the enlarged portion 67 lifts away from the seat in the bottom wall of the piston 69. The cam 85 and its drive mechanism are enclosed in a suitable oil-tight housing not shown, the interior of which is connected to tank.

The entire arrangement of the control unit 52 is such that whenever a shot of oil is admitted through the conduit 56 to the chamber 79, the piston 69 is lifted due to the enlarged portion 67 being on its seat in the bottom wall of the piston 69. The piston 69 and both valves 45 and 51 are accordingly lifted to a position just short of the highest position to which the cam would lift them. Thus the valve 45 is opened and the valve 51 is reversed to cause the stroke of the pump 46 to be increased at a rate determined by the volumetric capacity of the auxiliary pump 48. Oil is delivered to and returned from the fluid motor 42 through the conduits 54, 47, and 53, thus causing the motor 42 to operate, turning the cam 85. The latter will contact the roller 83 after about $\frac{1}{4}$ of a revolution when the highest part of the cam strikes the roller 83, thus lifting the valves 45 and 51 a further amount. This additional lift raises the enlarged portion 67 off from the seat in the bottom wall of the piston 69, thus permitting the oil trapped in the chamber 79 to escape through the opening in the bottom wall of the piston 69 and through the passage 81 to tank. As soon as the cam has completed an approximate $\frac{1}{2}$ revolution in addition, the roller 83 drops down to the cam portion 87, thus reversing connections at valve 57 but not completely closing the valve 45. The stroke of the pump 46 is thus reduced at a rate determined by the capacity of pump 48 causing the motor 42 to decelerate. When the cam 85 has completed a revolution, the roller 83 returns to the position shown in the drawings, completely closing the valve 45. At this time the enlarged portion 67 again comes to rest on its seat in the bottom wall of piston 69, thus placing the apparatus in condition for restarting whenever another shot of oil is introduced to the conduit

56. It will be noted that should a shot of oil be introduced to the conduit 56 before the cam 85 has made one revolution, the lift piston 69 will not rise because a free path is opened from the chamber 79 to tank through the passage in which the enlarged portion 67 seats. It will also be noted that oil pressure from the auxiliary pump is constantly exerted over the upper end of the valve 57 creating a bias for the entire stem assembly in the downward direction. Likewise this pressure is exerted over the annular area at the top of the portion 71 of the lift piston 69 biasing the latter downwardly whenever pressure is relieved in the chamber 79 by the opening of the passage through the bottom wall of the piston 69.

The casing 34 is provided on its front face with an outward extension 58 having an opening 60 of proper size and shape to permit a piece of ammunition to pass therethrough. The extension 58 is hinged to the casing at 62 along one edge thereof and is adapted to be clamped in sealing engagement therewith by suitable securing means 64. The extension 58 is formed with a cylindrical recess 66 within which is mounted a transfer cylinder 68. The cylinder 68 is pivoted on bearings 70 which are in turn mounted on studs 72 threaded into the extension 58 for permitting assembly of the cylinder 68 therein. The cylinder 68 is provided with a recess 74 of suitable shape to receive a piece of ammunition within the confines of the cylinder so that the latter may rotate between the position illustrated and a position 180° away, in which the recess 74 is in register with the opening 60. Spring retaining clips 76 are secured in the walls of the recess 74 for frictionally retaining ammunition in the recess. An ejector arm 78 is pivoted at 80 in the cylinder 68 and has an operating arm 82 in engagement with a pin 84 on a bar 86 slideable in a bore 88. A spring 90 biases the bar 86 downwardly and the ejector arm 78 toward the back of the recess 74 to lie within a suitable recess 92 adjacent the recess 74.

The lower end of the cylinder 68 has secured thereto a bevel gear 94 which is positioned within a recess 96 so formed that the cylinder 68 with gear 94 attached may be inserted in the extension 58 by laterally sliding the same into the recess 66 from the conveyer chain side thereof when the extension 58 is swung away from the casing 34. A bevel gear 98 meshes with the gear 94 and is rigidly secured to a crankshaft 100 mounted in a bearing 102 and having a handle 104 whereby the cylinder 68 may be manually rotated. Suitable means are provided for limiting the rotation of the cylinder 68 to 180° and for this purpose conveniently, the gear 94 may be formed with blank teeth on a portion of its periphery.

The casing 34 is provided below the extension 58 with an opening 106, sealed by a casing member 108. Journalled between the casing 34 and the casing 108 is a shaft 110 carrying a trip arm 112 and a pinion 114. The former projects into the path of the carrying lugs 39 so that in the rest position of the chain 38 the lug 112 is held in the position shown in Fig. 2.

The pinion 114 meshes with a pinion 116 secured to a shaft 118 journalled in the casing member 108 and extending outwardly on both sides thereof. The shaft 118 carries an arm 120 connected to a bar 122 slideable in a bore 124 in the extension 58. Bore 88 and bar 86 are adapted to register with the bar 122 and the bore 124 whenever the cylinder 68 lies in the position illustrated in the drawings. A spring 126 biases the bar 122 downwardly to retract the same when-

ever the trip arm 112 is released by the lug 39. The trip arm 112 is connected to the pinion 114 through a spring biased lost motion connection illustrated in Figs. 6 and 7. For this purpose the arm 112 has a hub 128 having a projecting portion 130 thereon. The pinion 114 has a hub 132 surrounding the hub 128 and provided with a recess 134 of greater circumferential extent than the projection 130. A spring 136 is connected between the arm 112 and the pinion 114 to urge the latter clockwise in Figs. 2 and 6. The spring 136 is of sufficient strength to predominate over the springs 126 and 90.

Pivotedly mounted in the casing 34 adjacent the extension 58 are a pair of barriers or flapper doors 138 adapted to rest against the surface of the cylinder 68. The doors 138 are of sufficient width to prevent ammunition from accidentally falling from the recess 74 on to the conveyer chain 38 when the doors are in the dotted line position. The doors 138 extend the full length of the recess 74 and have sealing engagement with the top and bottom walls thereof. The doors 138 are mounted on pivot shafts 140 which project below the extension 58 and carry bevel gears 142 meshing with bevel gears 144 secured to the shaft 118.

Pivotedly mounted in the casing 34 adjacent the lower edge of the recess 66 at 146 is a lower trip arm 148 adapted to be depressed by a piece of ammunition such as 150 when it is placed in position on the hoist chain 38. The lower trip 148 is connected by an arm 152 to a lower trip valve 154 mounted in a valve block 156. An upper trip valve 158 is also mounted in the block 156 and is adapted to be actuated by a solenoid 160 which in turn is controlled by an upper trip 162 located at the delivery end of the hoist. The valve 154 is adapted to connect a conduit 164 with a conduit 166 when the trip 148 is depressed and to connect conduit 164 with a conduit 168 when the trip 148 is raised. The valve 156 is adapted to open communication between the conduit 164 and the conduit 56 whenever the solenoid 160 is energized and to close communication when the solenoid is deenergized.

The solenoid 160 is under the control of upper trip 162 through a three-way switch 170 which is connected in circuit with a three-way switch 172 adapted to be actuated by a reversing lever 174. When the reversing lever 174 is set to hoist ammunition as illustrated in Fig. 4, the switch 172 connects the solenoid to the switch 170 so that the solenoid will be energized whenever the trip 162 is released by the removal of ammunition from the delivery end of the hoist. With reverse lever 174 set for lowering ammunition the switch 172 connects the solenoid 160 to the switch 170 for opposite action. The lever 174 also controls a reversing valve 176 for selectively connecting either the conduit 166 or the conduit 168 with a conduit 178 leading from the auxiliary pump 48, as well as controlling valve 51 for reversing operation of motor 42.

In operation, with motor 50 and pumps 46 and 48 running, and with the hoist at rest due to the presence of a piece of ammunition at the delivery station, trip 162 keeps the solenoid 160 deenergized so that pressure fluid from the pump 48 is blocked off from the conduit 56 at the valve 158. Assuming a piece of ammunition to have been ejected from the recess 74 and to lie on the chain 38 and the lower trip 148; as soon as the ammunition is removed from the delivery station, trip 162 is released to energize solenoid 160 opening valve 158 to admit pressure fluid to the conduit 56. It will be noted that at the instant of starting, the bar

122 is projected into the bore 88 by the action of the trip arm 112 which is engaged by the carrying lug 39, so that cylinder 68 is effectively locked against rotation. The control unit 58 in response to the admission of pressure fluid to the conduit 56 causes the fluid motor 42 to drive the sprockets 40 and chain 38 through one flight; that is, through the distance required to bring the next lug 39 into rest position as illustrated in Fig. 2. As soon as the chain 38 starts to move, the trip arm 112 is released and springs 90 and 126 force the bars 86 and 122 downwardly, thus retracting the ejector arm 78 and withdrawing the bar 122 from the bore 88. The cylinder 68 is thereby unlocked so that it may be rotated half a revolution by operation of the crank handle 104. This brings the recess 74 into register with the opening 60 so that a piece of ammunition may be placed in the recess 74 and the crank 104 may be again operated to return the cylinder 68 to the position shown.

If this sequence of operations of the cylinder 68 be completed before the hoist chain 38 has completed one flight, the flapper doors 138 will lie in contact with the cylinder 68, as illustrated by dotted lines in Fig. 5, thus positively retaining the ammunition against accidental displacement from the recess 74. As soon as the chain 38 comes to the end of its flight the next lug 39 again actuates the trip arm 112 to open the flapper doors 138 and to operate the ejector arm 78, thus positively displacing the ammunition from the recess 74 to the proper position on the chain 38. The hoist is then ready for another cycle of operation as soon as the piece of ammunition is removed from the delivery end of the hoist.

Should the hoist chain 38 complete its flight before the cylinder 68 has been returned to the position illustrated, the lug 39 will actuate the trip arm 112 but since the bore 88 is not in register with the bar 122 it is impossible for the pinions 114 and 116, operating arm 120 and the flapper door pivot shafts 140 to move. Under these conditions the movement of the trip arm 112 takes up the lost motion between the arm 112 and the pinion 114 and further tensions the spring 136. Thereafter as soon as cylinder 68 is brought into ejecting position, the bar 122 moves into bore 88 under the urge of spring 136 and the operation continues as before.

If at any time during the operation of the hoist an accidental explosion should occur adjacent the gun or in the hoist trunk itself due to a hit by an enemy shell, the transmission of flare-backs or flame travel of any kind to the compartments 24 and 30 is effectively prevented at the loading stations 25 and 32. It will be noted that no matter what the position of the cylinder 68 there is no path for flame to travel from the interior of the casing 34 to the exterior thereof. Thus, when the cylinder 68 is in the position shown in the drawing the cylinder itself forms a seal at the opening 60 by its engagement with the walls thereof. Any gas pressure existing in the casing 34 above the pressure outside thereof tends to force the cylinder 68 into tighter engagement with the walls of the opening 60. In all other positions of the cylinder 68, the flapper doors 138 are maintained in sealing engagement with the walls of the cylinder 68 by the action of spring 126 which tends to force the lever 120 downwardly thus urging the shafts 140 in the direction for closing the flapper doors 138. The distance from the point of contact of the flapper doors 138 with the cylinder 68 to the point of

engagement of cylinder 68 with the side walls of the opening 60 is greater than the width of the recess 74. By this construction it is thus insured that the opening through which ammunition is passed to the hoist chain 38 is maintained sealed at all times.

The cylinder 68 being pivoted on a non-vertical axis and having a non-symmetrically disposed center of gravity tends always to assist the operator of the crank handle 104. Thus, in moving the empty cylinder from the position shown, to the position for loading the recess 74, the heaviest part of the rotating mass is above its center of rotation so that once it is moved off from dead center, the natural tendency is to rotate to the position for loading the recess 74. Likewise, when the recess 74 is loaded, the center of gravity of the combined cylinder and ammunition is again above the center of rotation so that the loaded cylinder tends to move to the position shown. To make use of this feature to the greatest extent it is desirable to proportion the mass of the cylinder 68 relative to that of the ammunition 150 in such a manner that the unbalanced mass of cylinder 68 is substantially half the mass of the ammunition 150 and that its center of gravity is located at a radius from the center of rotation equal to the radius of the center of gravity of the ammunition from the center of rotation.

While the form of embodiment of the invention as herein disclosed, constitutes a preferred form, it is to be understood that other forms might be adopted, all coming within the scope of the claims which follow.

What is claimed is as follows:

1. In a conveyer for delivering ammunition between a loading station adjacent a storage compartment and a station for use and having an endless flexible ammunition conveyer band, a flame-proof casing surrounding the conveyer band and means for driving the conveyer band in intermittent cycles of movement, the combination with the conveyer of means for passing ammunition into said casing at the loading station, means cooperating with the ammunition passing means for maintaining a flame-proof seal between the inside and outside of the casing at all times, and means preventing initiation of a cycle of the conveyer band until the ammunition passing means has operated to position a piece of ammunition on the conveyer band.
2. In a conveyer for delivering articles between two stations the combination of an endless flexible conveyer band, means for driving said conveyer band in intermittent cycles of movement, means forming a flame-proof wall between said conveyer band and one of said stations, said wall having an opening adjacent the conveyer band through which articles may pass, means associated with said opening for passing articles therethrough and cooperating with said opening for maintaining said opening sealed against the passage of flame, and means preventing initiation of a cycle of the conveyer band until the article passing means has positioned an article on the conveyer band.
3. In a conveyer for delivering ammunition between a loading station adjacent a storage compartment and a station for use and having an endless flexible ammunition conveyer band, a flame-proof casing surrounding the conveyer band and means for driving the conveyer band in intermittent cycles of movement, the combination with the conveyer of means for passing ammunition into said casing at the loading sta-

tion, means for controlling the operation of the ammunition passing means in accordance with operation of the conveyer band, means cooperating with the ammunition passing means for maintaining a flame-proof seal between the inside and outside of the casing at all times, and means preventing initiation of a cycle of the conveyer band until the ammunition passing means has operated to position a piece of ammunition on the conveyer band.

4. In a conveyer for delivering ammunition between a loading station adjacent a storage compartment and a station for use and having an endless flexible ammunition conveyer band provided with a plurality of ammunition carrying lugs, a flame-proof casing surrounding the conveyer band and means for driving the conveyer band in intermittent cycles of movement starting and terminating with a lug in a predetermined position, the combination with the conveyer of means for passing ammunition into said casing at the loading station including a rotatable cylinder having an ammunition receiving recess and spaced from said conveyer band sufficiently to permit said lugs and the ammunition carried thereby to pass said cylinder in all positions thereof, means cooperating with the ammunition passing means for maintaining a flame-proof seal between the inside and outside of the casing at all times, and means for positively ejecting ammunition from said recess on to the conveyer band.

5. In a conveyer for delivering ammunition between a loading station adjacent a storage compartment and a station for use and having an endless flexible ammunition conveyer band, a flame-proof casing surrounding the conveyer band and means for driving the conveyer band, the combination with the conveyer of means for passing ammunition into said casing at the loading station including a rotatable cylinder having an ammunition receiving recess, means forming a casing for said cylinder and having a loading opening with which said recess may register in one position of the cylinder, means for rotating said cylinder to and from a position in which the recess is adjacent to and facing the conveyer band, and means in addition to said casing for forming a flame-proof seal between the interior of said fluidtight casing and the cylinder, said cylinder engaging its casing to form a flame-proof seal between the cylinder and the opening.

6. In a conveyer for delivering ammunition between a loading station adjacent a storage compartment and a station for use and having an endless flexible ammunition conveyer band, a flame-proof casing surrounding the conveyer band and means for driving the conveyer band, the combination with the conveyer of means for passing ammunition into said casing at the loading station including a rotatable cylinder having an ammunition receiving recess, means forming a casing for said cylinder and having a loading opening with which said recess may register in one position of the cylinder, means for rotating said cylinder to and from a position in which the recess is adjacent to and facing the conveyer band, and means for ejecting ammunition laterally from said recess on to the conveyer band, and controlled in accordance with the operation of the conveyer band.

7. In a conveyer for delivering ammunition between a loading station adjacent a storage compartment and a station for use and having an endless flexible ammunition conveyer band, a

- flame-proof casing surrounding the conveyer band and means for driving the conveyer band, the combination with the conveyer of means for passing ammunition into said casing at the loading station including a rotatable cylinder having an ammunition receiving means, means forming a casing for said cylinder and having a loading opening with which said recess may register in one position of the cylinder, means for rotating said cylinder to and from a position in which the recess is adjacent to and facing the conveyer band, and means including a displaceable barrier forming a flame-proof seal between the interior of said fluidtight casing and the cylinder, said cylinder engaging its casing to form a flame-proof seal between the cylinder and the opening.
8. In a conveyer for delivering ammunition between a loading station adjacent a storage compartment and a station for use and having an endless flexible ammunition conveyer band, a flame-proof casing surrounding the conveyer band and means for driving the conveyer band, the combination with the conveyer of means for passing ammunition into said casing at the loading station including a rotatable cylinder having an ammunition receiving recess, means forming a casing for said cylinder and having a loading opening with which said recess may register in one position of the cylinder, means for rotating said cylinder to and from a position in which the recess is adjacent to and facing the conveyer band, means including a displaceable barrier forming a flame-proof seal between the interior of said fluidtight casing and the cylinder, said cylinder engaging its casing to form a flame-proof seal between the cylinder and the opening, means for ejecting ammunition from said recess, and means for displacing said barrier, both last named means being controlled in accordance with the operation of the conveyer band.
9. In a conveyer for delivering ammunition between a loading station adjacent a storage compartment and a station for use and having an endless flexible ammunition conveyer band, a flame-proof casing surrounding the conveyer band and means for driving the conveyer band, the combination with the conveyer of means for passing ammunition into said casing at the loading station including a rotatable cylinder having an ammunition receiving recess, means forming a casing for said cylinder and having a loading opening with which said recess may register in one position of the cylinder, means for rotating said cylinder to and from a position in which the recess is adjacent to and facing the conveyer band, means including a displaceable barrier forming a flame-proof seal between the interior of said fluidtight casing and the cylinder, said cylinder engaging its casing to form a flame-proof seal between the cylinder and the opening, means for ejecting ammunition from said recess, and means for displacing said barrier, both last named means being controlled in accordance with the operation of the conveyer band.
10. In a conveyer for delivering ammunition between a loading station adjacent a storage compartment and a station for use and having an endless flexible ammunition conveyer band, a flame-proof casing surrounding the conveyer band and means for driving the conveyer band, the combination with the conveyer of means for passing ammunition into said casing at the loading station including a rotatable cylinder having an ammunition receiving recess, means forming

a casing for said cylinder and having a loading opening with which said recess may register in one position of the cylinder, means for rotating said cylinder to and from a position in which the recess is adjacent to and facing the conveyer band, means including a displaceable barrier forming a flame-proof seal between the interior of said fluidtight casing and the cylinder, said cylinder engaging its casing to form a flame-proof seal between the cylinder and the opening, means for displacing said barrier, controlled in accordance with the operation of the conveyer band, and means for preventing rotation of the cylinder while said barrier is displaced.

11. In a conveyer for delivering ammunition between a loading station adjacent a storage compartment and a station for use and having an endless flexible ammunition conveyer band, a flame-proof casing surrounding the conveyer band and means for driving the conveyer band, the combination with the conveyer of means for passing ammunition into said casing at the loading station including a rotatable cylinder having an ammunition receiving recess, means forming a casing for said cylinder and having a loading opening with which said recess may register in one position of the cylinder, means for rotating said cylinder to and from a position in which the recess is adjacent to and facing the conveyer band, said cylinder being pivoted on a non-vertical axis and having its center of gravity opposite said recess sufficiently so that when said recess is empty the cylinder will tend to rotate to position with the recess in register with the loading opening and when ammunition is in said recess the cylinder will tend to move to the opposite position.

12. In a conveyer for delivering articles between two stations the combination of an endless flexible conveyer band, means for driving said conveyer band, means forming a flame-proof wall between said conveyer band and one of said stations, said wall having an opening adjacent the conveyer band through which articles may pass, means associated with said opening for passing articles therethrough including a rotatable cylinder having an article receiving recess and cooperating with said opening for maintaining said opening sealed against the passage of flame, and means forming a flame-proof seal between said cylinder and the space on the conveyer band side of said wall in addition to the seal maintained between the cylinder and the opening.

13. In a conveyer for delivering articles between two stations the combination of an endless flexible conveyer band, means for driving said conveyer band, means forming a flame-proof wall between said conveyer band and one of said stations, said wall having an opening adjacent the conveyer band through which articles may pass, means associated with said opening for passing articles therethrough including a rotatable cylinder having an article receiving recess and cooperating with said opening for maintaining said opening sealed against the passage of flame, and means including a displaceable barrier forming a flame-proof seal between said cylinder and the space on the conveyer band side of said wall in addition to the seal maintained between the cylinder and the opening.

14. In a conveyer for delivering articles between two stations the combination of an endless flexible conveyer band, means for driving said conveyer band, means forming a flame-proof wall between said conveyer band and one of said stations, said wall having an opening adjacent the

conveyer band through which articles may pass, means associated with said opening for passing articles therethrough including a rotatable cylinder having an article receiving recess and cooperating with said opening for maintaining said opening sealed against the passage of flame, and a displaceable barrier for at times preventing the passage of articles from said recess into position on said conveyer band.

15. In a conveyer for delivering articles between two stations the combination of an endless flexible conveyer band, means for driving said conveyer band, means forming a flame-proof wall between said conveyer band and one of said stations, said wall having an opening adjacent the conveyer band through which articles may pass, means associated with said opening for passing articles therethrough including a rotatable cylinder having an article receiving recess and cooperating with said opening for maintaining said opening sealed against the passage of flame, a displaceable barrier for at times preventing the passage of articles from said recess into position on said conveyer band, and means for displacing said barrier in accordance with the operation of the conveyer band.

16. In a conveyer for delivering articles between two stations the combination of an endless flexible conveyer band, means for driving said conveyer band, means forming a flame-proof wall between said conveyer band and one of said stations, said wall having an opening adjacent the conveyer band through which articles may pass, means associated with said opening for passing articles therethrough including a rotatable cylinder having an article receiving recess and cooperating with said opening for maintaining said opening sealed against the passage of flame, and means forming a flame-proof seal between said cylinder and the space on the conveyer band side of said wall in addition to the seal maintained between the cylinder and the opening, said cylinder being pivoted on a non-vertical axis and having its center of gravity opposite said recess sufficiently so that when said recess is empty the cylinder will tend to rotate to position with the recess in register with the loading opening and when an article is in said recess the cylinder will tend to move to the opposite position.

17. In a conveyer for delivering ammunition between a loading station adjacent a storage compartment and a station for use and having an endless flexible ammunition conveyer band, a flame-proof casing surrounding the conveyer band, the combination with the conveyer of means for passing ammunition into said casing at the loading station including a rotatable cylinder having an ammunition receiving recess, means forming a casing for said cylinder and having a loading opening with which said recess may register in one position of the cylinder, means for rotating said cylinder to and from a position in which the recess is adjacent to and facing the conveyer band, a displaceable barrier positioned between the recess and the conveyer band, and means for displacing said barrier, operated from said driving means.

18. In a conveyer for delivering ammunition between a loading station adjacent a storage compartment and a station for use and having an endless flexible ammunition conveyer band, a flame-proof casing surrounding the conveyer band and means for driving the conveyer band,

the combination with the conveyer of means for passing ammunition into said casing at the loading station including a rotatable cylinder having an ammunition receiving recess, means forming a casing for said cylinder and having a loading opening with which said recess may register in one position of the cylinder, means for rotating said cylinder to and from a position in which the recess is adjacent to and facing the conveyer band, a displaceable barrier positioned between the recess and the conveyer band and means for displacing said barrier in predetermined relation to the rotation of said cylinder.

19. In a conveyer for delivering ammunition between a loading station adjacent a storage compartment and a station for use and having an endless flexible ammunition conveyer band provided with a plurality of ammunition carrying lugs, a flame-proof casing surrounding the con-

veyer band and means for driving the conveyer band in intermittent cycles of movement starting and terminating with a lug in a predetermined position, the combination with the conveyer of means for passing ammunition into said casing at the loading station including a rotatable cylinder having an ammunition receiving recess and spaced from said conveyer band sufficiently to permit said lugs and the ammunition carried thereby to pass said cylinder in all positions thereof, means cooperating with the ammunition passing means for maintaining a flame-proof seal between the inside and outside of the casing at all times, and means for positively ejecting ammunition from said recess on to the conveyer band, controlled in accordance with the operation of the conveyer band.

WILLIAM THOMAS.
